Patented Mar. 1, 1921.

INVENTOR

GEORGE H. MOFFETT.

BY

R. D. Shumate

ATTORNEY

UNITED STATES PATENT OFFICE.

GRAY H. MOFFETT, OF BIRMINGHAM, ALABAMA.

STOVEPIPE-HOLDER.

1,369,831.

Specification of Letters Patent.

Patented Mar. 1, 1921.

Application filed October 31, 1919. Serial No. 334,899.

To all whom it may concern:

Be it known that I, GRAY H. MOFFETT, a citizen of the United States of America, residing at Birmingham, in the county of Jefferson and State of Alabama, have invented certain new and useful Improvements in Stovepipe-Holders, of which the following is a specification.

My invention relates to an improved type 10 of stove pipe holder which is especially adapted for use with different thicknesses of flue walls.

My invention contemplates the provision of an adjustable bracket anchored at its 15 forward end preferably by attachment to the stove pipe collar and having its rear end projecting deeply into the chimney flue and provided with a downwardly and forwardly inclined leg which, due to its length 20 and flexibility, can be bent to fit flue walls within the customary variations in thickness.

A further object of my invention is to adapt the bracket on its portion which over- 25 hangs within the flue to hold an adjustable clip which serves to stop and interlock with the inner end of the stove pipe.

My invention also comprises the novel 30 details of construction and arrangements of parts, which in their preferred embodiment only, are illustrated in the accompanying drawings, in which—

Figure 1 is a vertical sectional view 35 through the flue walls showing my apparatus in side elevation.

Fig. 2 is a perspective view of my invention, the dotted line showing the bracket leg adjusted to fit a thicker flue wall.

Fig. 3 is a detailed view of the adjustable 40 pipe holding clip.

Similar reference numerals refer to similar parts throughout the drawings.

I have illustrated my invention in connection with a chimney flue 1 having a front 45 wall 2 provided with the customary hole for the reception of the inner end of the stove pipe 3. A collar 4 surrounds the pipe and conceals the pipe hole in the customary manner.

50 My invention comprises a bracket adapted to be inserted through the stove pipe hole with a top leg 5 which projects outwardly through the hole below the pipe and has its outer end down-turned at 6 and provided 55 with a bolt hole to receive the bolt 7 which attaches it to the collar 4. It will be ob-

served that the top member 5 of the bracket projects deeply into the chimney flue and then joins the downwardly and forwardly inclined flexible member 7 which at its forward end is down-turned at 8 forming a flange which engages the inner face of the front flue wall 2. By bending this member 7 down, as illustrated by dotted line showing in Fig. 2, it will be apparent that the 60 bracket can be set to flue walls 2 of any ordinary variation in thickness, thus enabling the same bracket to have almost universal use and avoiding the necessity of stocking different sized brackets to fit different thicknesses of flue walls.

At a point on the bracket member 5 which would project beyond flue walls of minimum thickness I provide a series of adjustment holes and a screw bolt 9 is passed through one of these holes 8^a to secure on the top face of the member 5 a stove pipe holding clip 10. This clip is mounted on the bracket in position to bring its hook-like end 11 into position at the inner end of the flue hole and a lip 12 is provided by bending up the inner end of the stove pipe and adapted to be shifted into interlocking engagement with the hook 11 after the pipe has been thrust the proper distance into the flue hole and turned about its long axis. The clip is provided at its rear end with a depressed tongue 13 so spaced relatively to the bolt hole in the clip that this tongue will engage in one of the holes 8^a and by this 75 arrangement the clip is held from turning about the bolt and can be adjusted lengthwise along the bracket until the tongue reaches the innermost hole 8^a. The length of the bracket is such that the range of adjustment for the clip will take care of the 80 normal variations of the thickness of the flue wall 2.

In operation, the front flange 6 of the bracket is bolted to the collar and the bracket 100 is thrust through the stove pipe hole, the member 7 having previously been adjusted to the thickness of the wall 2 and adapted, when in position, to yieldingly engage the flue wall and exert a spring pressure which 105 tends to draw the collar to the wall and hold it firmly in place. The clip 10, prior to mounting the bracket, has been adjusted to bring its hook in position to overhang into the inner end of the flue hole. The 110 stove pipe then has a lip 12 bent up at its inner end and is thrust through the collar

until its end strikes the clip when the pipe is turned until its lip 12 interlocks with the clip hook 11, whereupon it will be seen that the clip will prevent axial movement in either direction of the stove pipe and will hold the latter and the collar yieldingly in position.

My invention may be varied in its detailed construction without departing from the novel principles set forth in the appended claims.

Having thus described my invention what I claim as new and desire to secure by Letters Patent, is:—

1. A stove pipe and collar holder, comprising a bracket having a top member which projects through the stove pipe flue hole and overhangs deeply into the flue and is there joined by a down-turned forwardly inclined member adapted to be bent relatively to the bracket top to adjust it to varying thicknesses of flue walls, in combination with means to affix the forward end of the top bracket member to a stove pipe collar, and means to mount an adjustable pipe stop and fastening clip on the overhung inside portion of the bracket.

2. A stove pipe holder comprising, in combination, a bracket formed of a bent metal bar having a horizontal top leg and a down-

wardly and forwardly inclined flexible brace leg at the inner end of said leg which overhangs substantially beyond the flue hole and into the stove pipe flue, and means to adjustably mount on the overhung inner end of said bracket leg a stove pipe engaging clip, substantially as described.

3. The combination with the stove pipe, a collar therefore, and a flue having a hole for the stove pipe, of a bracket formed of a bent metal bar having its upper leg inserted through the flue hole, means to attach the outer end of said bracket leg to the collar, the inner end of said bracket leg projecting a substantial distance beyond the surface of flue wall and having perforations in its overhung portion, a clip adjustably mounted on the bracket by anchoring means passing through said perforations, means to interlock the inner end of the stove pipe with said clip to hold the pipe against axial movement, and a long, forwardly and downwardly inclined leg of the bracket adapted to be bent to yieldingly engage the inner surface of flue walls of varying thickness, substantially as described.

In testimony whereof I affix my signature.
GRAY H. MOFFETT.
